FLUID BUFFER FOR ELEVATORS**Walter Beck, Rock Island, Ill., assignor to Montgomery Elevator Company, a corporation of Illinois****Application September 27, 1952, Serial No. 311,901****6 Claims. (Cl. 187—67)**

This invention relates to improvements in fluid elevator buffers and particularly to improvements in construction which reduce the cost, facilitate the servicing and improve the operation of such buffers.

For many years, fluid buffers have been used as safety devices with elevators. Basically, such buffers comprise a fluid filled cylinder with a piston movable therein. The buffer is placed at the bottom of the elevator pit in such a position that the piston rod will be contacted by the descending elevator cage or counterweight. If all of the other safety devices, such as friction brakes and limit switches, should fail and the elevator or the counterweight descend into the pit, its fall will be arrested and the shock of stopping will be cushioned by the oil damped piston. In the usual installation, two buffers are provided, one for the cage and the other for the counterweight. Generally, these buffers also include a fluid reservoir surrounding the cylinder and a rather complex head casting which serves as an auxiliary reservoir and which provides means for guiding the piston rod. The complexity of this head casting makes it difficult and costly to manufacture.

One object of my invention is to provide an improved fluid elevator buffer. Another object is to provide such a buffer in which the reservoir is provided with a substantially planar closure member of substantially the same area as the reservoir, so as to avoid the need for a casting with a closed top and a partially closed bottom, with the resulting complexity of coring the casting. Yet another object is to provide a buffer in which the cylinder in which the piston travels is shorter than the surrounding reservoir, and the member on top of the reservoir is provided with positioning means which engage the cylinder. Still another object is to provide such a buffer with a filler tube attached to the reservoir and having the point of filling below the top of the cylinder.

Further objects and advantages will become apparent from the following specification and from the drawings in which:

Fig. 1 is a side elevation of a lever type elevator buffer showing the elevator cage at ground level;

Fig. 2 is a side elevation, similar to Fig. 1, but showing the elevator cage after it has descended into the pit, with the buffer in fully depressed position;

Fig. 3 is an enlarged sectional view taken as indicated along the line 3—3 in Fig. 4, with the spring guide member removed for added clarity;

Fig. 4 is an end elevation of the buffer, viewing Fig. 1 from the right, with some portions in section;

Fig. 5 is a fragmentary sectional view taken as indicated along the line 5—5 of Fig. 4; and

Fig. 6 is a diagrammatic sketch showing the relative movement of the lever and the yoke.

In the embodiment illustrated in the drawings, the invention is shown in connection with a lever type buffer as opposed to a straight-line, or standard type buffer. As will become evident, either type of buffer may be

2

used. The straight-line buffer is generally installed in locations where the depth of the elevator pit is not critical. The lever type buffer was designed for use in situations where for some reason, such as where a building is built on bed rock, it is impractical or impossible to dig a pit deep enough to accommodate a standard buffer which may be almost 11 feet long in extended position and have a stroke of 4½ feet. A representative lever buffer may be less than 3 feet long, have a piston stroke of 7 inches and a lever arm movement of 2½ times the piston stroke.

Referring now to Fig. 1, the elevator cage 10 is shown with its floor 11 flush with the ground 12; and a lever type buffer, indicated generally at 13, is shown in a pit 14 beneath the elevator cage in its normal or raised position. Details of the elevator construction are omitted for the sake of simplicity.

The buffer 13 is provided with lever means 15 which is so positioned that if the other safety devices, such as friction brakes, motor speed governors, electro-magnetic brakes and limit switches, fail to operate and the cage 10 descends below the ground level 12, it strikes the lever means 15 so that its descent is arrested by the buffer and it comes to rest in the position shown in Fig. 2.

Referring now to Figs. 4 and 5, it will be seen that the lever type buffer 13 has a base consisting of a pair of upright channel members 16, and a transverse channel member 17. The base also includes a pair of upright extending legs 18 to which the lever means 15 are pivotally attached.

A reservoir 19 is secured to the transverse channel member 17 and extends upwardly therefrom. As shown here, this reservoir is cylindrical in shape; but it could take other forms, such as a rectangle. The top of the reservoir 19 is fitted with a closure member 20, which is sealed thereto by means of studs 21 welded to the reservoir and nuts 22. The closure member 20 has roughly the same cross sectional area as the reservoir, and is substantially planar. The closure member is provided with a downwardly extending positioning boss 23 which extends into the reservoir and is provided with a plurality of radial positioning fins 23a.

The manner in which the closure member 20 is fitted to the reservoir 19 should be noted particularly. In the past, these buffers have been constructed with the various parts threaded together, and as the diameters involved were rather large, the reservoir possibly being 8 inches in diameter, it was extremely difficult to maintain the desired standards of length or overall dimensions in the finished product. In the buffer shown, the abutting surfaces of the reservoir and the closure member are finished with a relatively high degree of accuracy, and the parts are then bolted together. This method of construction is now followed throughout, as will be seen.

A cylinder 24 is mounted on a block 25 inside the reservoir. The upper end 26 of the cylinder is spaced below the closure member 20, and engages the positioning fins 23a. The top of the cylinder is open to the reservoir through the cavities 36 between the fins. A plurality of apertures 27 are provided in the wall of the cylinder 24 communicating between the reservoir and the interior of the cylinder. The function of these apertures and the reason for the particular arrangement used will be explained later. A piston 28 is movable longitudinally in the cylinder, and the piston rings 29 provide a seal between the piston and the walls of the cylinder. A hollow, tubular piston rod 30 is affixed to the piston 28 and extends upwardly through a bore 31 in the closure member 20 and boss 23. The end surfaces of the piston rod and the abutting shoulder of the piston are finished with a high degree of accuracy and the parts are held together by means of pins 32. The upper end of the

piston rod is provided with a cap 33, the abutting surfaces again being accurately finished and the parts held together by pins 34. An O ring 35 provides an airtight seal between the cap 33 and the piston rod 30. A leather washer 37 encircles the piston rod 30 between the piston 28 and the positioning boss 23, cushioning the parts during operation. An oil seal 38 in a recess in the top of the closure member 20 and an O ring 39 in the bore 31 provide a fluid tight seal between the closure member and the piston rod 30.

A coil spring 41 extends between the upper surface of the plug 25 and the bottom surface of the cap 33 and biases the piston and piston rod upwardly. Spring guide member 42 is secured to the base of the cylinder and extends longitudinally through the spring to prevent it from buckling when compressed.

A cross bar 43 is bolted to the cap 33 and has bearing portions 43a and b at its ends on which links 44 and 45 are pivotally mounted to form a yoke structure. Two bifurcated levers are made up of the four elongated members 46a, 46b, 46c and 46d which are pivotally attached to the upright legs 18 by the pins 59 and to the links 44 and 45 by the pins 47 and 48.

Rollers 49 are mounted on an axle 50 at the outer extremity of the levers and are adapted to be contacted by the elevator cage or counterweight as shown in Fig. 6.

The interior of the piston rod 30 is vented to the atmosphere through the vent channel 51. A check valve comprising a ball 52 and annular seat 53 are provided in this channel and their operation will be explained later. The ball 52 is normally supported in the position shown by the pin 54.

The reservoir 19 may be filled with fluid through a filler tube 55 which is threaded into the side of the reservoir. The upper end 56 of the filler tube is below the top of the cylinder, and is closed by a removable plug 57. The level of the fluid, which may be a very light oil, in the reservoir is preferably as indicated by the line 58. It should be noted that the fluid entirely fills the cylinder below the piston.

In the event that the descending elevator mechanism engages the lever means 15 upon the failure of the other safeties as previously described, the lever means is rotated about the pins 59 and the piston 28 moves downwardly. The pressure of the air within the piston rod 30 is immediately increased, forcing the ball 52 into the annular seat 53 thereby closing the vent channel 51. Some of the oil within the cylinder 24 is forced up inside the piston rod, while most of it is ejected from the cylinder through the apertures 27 into the reservoir. The ring of apertures immediately beneath the piston 28 permits rapid ejection of oil so that the initial movement is rather rapid and the elevator does not receive an excessively severe jar. However, as the piston continues to descend under the impetus of the elevator mechanism, there are fewer apertures 27 through which the fluid may be ejected into the reservoir so that the descent of the piston is slowed until the bottommost aperture is passed and the piston and elevator mechanism are brought to rest. The oil that is forced from the cylinder into the reservoir rises in the reservoir and spills back over the open top of the cylinder through the cavities 36 and fills the cylinder above the piston 28. Thus, no additional fluid storage space is required.

Generally, when the elevator or counterweight descends into the elevator pit it is due to a failure in some portion of the control mechanism. It is desirable to prevent further operation of the elevator until the defective apparatus has been located and repaired. As shown in the drawings, an electric switch 61 is wired into the elevator motor and control circuits (not shown), and has an operating arm 62. A plate 63 attached to one of the lever arms 43 moves the operating arm 62 downward when the buffer is depressed, as shown in Fig. 2, to operate the switch 61 and prevent normal operation.

5 of the elevator motors and control circuits as long as the buffer is depressed.

After a defect has been remedied, the elevator mechanism may be raised from the pit and the buffer will resume its normal position, by virtue of the bias of the spring 41. The vent channel 51 will now be open, facilitating the recovery operation. The switch 61 will also return to its normal position, allowing the resumption of normal operation.

10 While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A fluid elevator buffer for use with a vertically reciprocable elevator mechanism, comprising: a base; a fluid reservoir mounted on said base, said fluid reservoir having a smoothly finished top margin; an open topped cylinder mounted in said reservoir with its upper end spaced substantially below the top margin of the reservoir, said cylinder having a plurality of apertures in its side wall; an effectively planar closure member for said fluid reservoir; said closure member having its periphery overlying the reservoir and having a smoothly finished surface to seat on the top margin of the reservoir; a plurality of attaching members sealing said closure member on the reservoir; a generally sleeve-like guide boss at the center of said closure member, said guide boss extending downwardly substantially to the top of the cylinder and having a plurality of outwardly extending spaced positioning fins engaging the top of the cylinder so as to leave upright fluid channels between the fins; a piston in the cylinder; a piston rod secured to the piston and extending through said guide boss in the closure member, said piston and piston rod being adapted to be depressed by the descending elevator mechanism; and means biasing said piston and piston rod upwardly.

2. The device of claim 1 in which the attaching members comprise means bearing on the top of the closure member and engaging lugs on the wall of the reservoir.

3. The device of claim 1 in which the attaching members comprise upstanding threaded lugs on the reservoir which project above the closure to receive threaded nuts.

4. A fluid elevator buffer for use with a vertically reciprocable elevator mechanism, comprising: a base; a fluid reservoir mounted on said base, said fluid reservoir having a smoothly finished top margin; an open topped cylinder mounted in said reservoir with its upper end spaced substantially below the top margin of the reservoir, said cylinder having a plurality of apertures in its side wall; an effectively planar closure member for said fluid reservoir; said closure member having its periphery overlying the reservoir and having a smoothly finished surface to seat on the top margin of the reservoir; a plurality of attaching members sealing said closure member on the reservoir; a generally sleeve-like guide boss at the center of said closure member, said guide boss extending downwardly substantially to the top of the cylinder and having a plurality of outwardly extending spaced positioning fins engaging the top of the cylinder so as to leave upright fluid channels between the fins; a piston in the cylinder; a piston rod secured to the piston and extending through said guide boss in the closure member, said piston and piston rod being adapted to be depressed by the descending elevator mechanism; means biasing said piston and piston rod upwardly; an elongated lever means attached to said piston rod, one end of said lever means being attached to said base and the other end being positioned to be contacted by the descending elevator mechanism.

5. A fluid elevator buffer for use with a vertically reciprocable elevator mechanism, comprising: a base; a fluid reservoir mounted on said base, said fluid reservoir having a smoothly finished top margin; an open topped

cylinder mounted in said reservoir with its upper end spaced substantially below the top margin of the reservoir, said cylinder having a plurality of apertures in its side wall; an effectively planar closure member for said fluid reservoir, said closure member having its periphery overlying the reservoir and having a smoothly finished surface to seat on the top margin of the reservoir; a plurality of attaching members sealing said closure member on the reservoir; integral sleeve-like guide means extending downwardly from the closure member into engagement with the top of the cylinder, said guide means having openings adjacent the top of the cylinder providing fluid passages between the cylinder and the reservoir; a piston in the cylinder; a piston rod secured to the piston and extending through said guide means in the closure member, said 15 piston and piston rod being adapted to be depressed by the descending elevator mechanism; and means biasing said piston and piston rod upwardly.

6. A fluid elevator buffer for use with a vertically reciprocable elevator mechanism, comprising: a base; 20 a fluid reservoir mounted on said base, said fluid reservoir having a smoothly finished top margin; an open topped cylinder mounted in said reservoir with its upper end spaced substantially below the top margin of the reservoir, said cylinder having a plurality of apertures in its side 25 wall; an effectively planar closure member for said fluid reservoir, said closure member having its periphery overlying the reservoir and having a smoothly finished surface to seat on the top margin of the reservoir; a plurality of attaching members sealing said closure member on the 30

reservoir; integral sleeve-like guide means extending downwardly from the closure member into engagement with the top of the cylinder, said guide means having openings adjacent the top of the cylinder providing fluid passages between the cylinder and the reservoir; a piston in the cylinder; a piston rod secured to the piston and extending through said guide means in the closure member, said piston and piston rod being adapted to be depressed by the descending elevator mechanism; means biasing said piston and piston rod upwardly; and elongated lever means attached to said piston rod, one end of said lever means being attached to said base and the other end being positioned to be contacted by the descending elevator mechanism.
